UNITED STATES PATENT OFFICE.

CLIFFORD M. WAY, OF DES MOINES, IOWA.

SCREEN.

1,345,569.

Specification of Letters Patent.

Patented July 6, 1920.

Application filed July 1, 1919. Serial No. 307,898.

To all whom it may concern:

Be it known that I, CLIFFORD M. WAY, a citizen of the United States, residing at Des Moines, in the county of Polk and State 5 of Iowa, have invented certain new and useful Improvements in Screens, of which the following is a specification.

The present invention relates to that type of screen for windows, doors, or the like, 10 which is provided with escape openings permitting free egress of flies or other insects from the interior to the outside when they follow their usual instinct of crawling upwardly on the screen. The object of these 15 improvements is to provide a simple means of forming the escape openings, and which may be easily and cheaply manufactured as well as quite readily attached by the user without special tools.

Another object in view is to provide means 20 of this character of such form or construction as to include bendable elements which will so coact with the screen frame as to constitute spacing members for holding the screen wire in spaced relation to said frame to thereby provide for the openings afore 25 said.

A further object in mind is to construct 30 the invention as a new article of manufacture in the form of a metal strip having at suitable intervals bendable extensions which not only form the spacing means mentioned but also constitute clamping means for the wire, tending to prevent injury 35 thereto from the stretching action, the strip being designed to lend itself most readily to compactness for shipping purposes, all as hereinafter more particularly pointed out.

These and such other objects as may here- 40 inaftter appear are attained by the novel construction, combination and arrangement of parts to be hereinafter specifically de- 45 scribed and claimed. Reference will now be had to the accompanying drawings forming a part of this specification, wherein:

Figure 1 is an elevation of a screen embodying my improvements.

Fig. 2 is a fragmentary sectional view, 50 enlarged, taken on the line 2-2 of Fig. 1. Fig. 3 is a similar sectional view taken on the line 3-3 of Fig. 1.

Fig. 4 is a sectional view of the line 4-4 of Fig. 1, and

Fig. 5 is a fragmentary view of the metal 55 strip showing one of the bendable exten-

sions adapted to form one of the spacing elements.

Throughout the following detail description and on the several figures of the drawings, similar parts are referred to by like 60 reference characters.

Referring to the drawing, 1 designates the frame of the screen which at the bottom and sides is provided with the finishing molding 2 holding the screen wire 3 against the 65 frame. In lieu of the use of such molding at the top of the frame, and preferably at the middle cross bar thereof, I utilize the spacing means which forms the main feature of my invention, said means consisting 70 of a narrow strip of metal 4 having at suitable intervals bendable extensions or flanges 5. In the manufacture of this strip these extensions are cut out in the usual manner and the strips may be supplied to purchasers 75 in flat condition so that advantage may be taken of compactness in shipping. In applying this spacing means to the frame the extensions 5 are first bent along the line *a*, at the juncture of said extensions with the 80 body of the strip, then backwardly along the line *b* midway of the length of the extension, thus bringing the end of the extensions against the inner face of the strip as shown most clearly in Figs. 2 and 3. It 85 will be apparent that this provides a lateral projection, triangular in form in cross section, and by providing the strip with apertures 6 and 7 the fastening means, or nails 8 may be driven through the strip and the 90 projections and fasten the strip against the face of the screen frame. When the extensions are bent in the manner referred to 95 the openings 6 and 7 come into alinement, but before driving the nails the upper edge 95 of the screen wire is inserted between the end of the extensions as shown in Figs. 2 and 3 so that when the nails are driven home the wire will be clamped against the inner face of the metal strip, which is of 100 considerable advantage in that it prevents the tendency of the wire to pull out owing to the tension on the screen wire. The ends of the strip are fastened under the ends of the finishing molding at the sides as shown 105 in Fig. 4 so that when properly applied the lateral projections formed by the extensions 5 hold the strip and wire in spaced relation to the screen frame and provide escape openings indicated at 9.

It will be apparent that this simple expedient may be readily carried out in the making of screens or in the modification of screens already constructed, to provide the escape openings referred to.

Having thus described my invention, what I claim as new is:

1. The combination with a frame and screen therefor, of means for holding the screen in spaced relation to said frame to provide escape openings, said means consisting of a metal strip having bendable flanges extending from one edge at intervals therealong, said flanges being adapted to be bent into offstanding position with respect to the face of the strip and against said face to receive and clamp the wire therebetween, and fastening means fastening through said strip and flanges for producing the clamping action.

2. As a new article of manufacture, a metal strip adapted for attachment to screens for windows, doors, or the like, said strip comprising spaced bendable extensions or flanges each adapted to be bent at the juncture of the flange and the strip to offstand from the face thereof and to be again bent back along a line substantially midway against the said face to receive and hold the wire screen against said face.

3. As a new article of manufacture a metal strip adapted for attachment to screens for windows, doors, or the like, said strip comprising lateral projections, triangular in cross section, the strip and projections being provided with aligned nail receiving openings whereby the strip may be held against the screen frame.

In testimony whereof I affix my signature.
CLIFFORD M. WAY.
